CLAIM

The ornamental design for a tool handle, as shown and described.

DESCRIPTION

FIG. 1 is an elevational view of an embodiment of a tool handle, showing my new design.

FIG. 2 is a perspective view of the invention illustrated in FIG. 1.

FIG. 3 is an enlarged view of a portion of the invention illustrated in FIG. 1.

FIG. 4 is a view like FIG. 1 and further illustrating the invention with a specific application denoted in broken lines; and,

FIG. 5 is an end view of the invention illustrated in FIG. 1. The broken lines of the figures represent the environmental structures for the illustrated tool handle and form no part of the claimed invention.

1 Claim, 4 Drawing Sheets
